(57) **CLAIM**

The ornamental design for a digital reader, as shown and described.

DESCRIPTION

FIG. 1 is a perspective view of a digital reader illustrating the top surface and having dashed lines disposed above buttons and representing operational indicators when the buttons are depressed.

FIG. 2 is a top plan of the invention having dashed lines disposed above buttons and representing operational indicators when the buttons are depressed.

FIG. 3 is a bottom plan of the invention.

FIG. 4 is a side elevational view of the invention.

FIG. 5 is side elevational view of the invention opposed to the side illustrated in FIG. 4.

FIG. 6 is an end elevational view of the invention.

FIG. 7 is an end elevational view of the invention opposed to the end illustrated in FIG. 6.

FIG. 8 is a perspective view of the invention illustrating the bottom surface; and,

FIG. 9 is a perspective view of the invention illustrating the top surface and having dashed lines representing part of the digital-reader cover which holds the invention.

The broken lines shown in the drawings represent portions of the digital reader and environmental structure that form no part of the claimed design.
